(57) **CLAIM**

The ornamental design for a thermal regulation vessel for individual bottle or other beverage container, as shown and described.

DESCRIPTION

FIG. 1 is a perspective view of a thermal regulation vessel for individual bottle or other beverage container in accordance with my new design;

FIG. 2 is a side view thereof, which side view is identical to all other side views thereof;

FIG. 3 is a top view thereof; and,

FIG. 4 is a bottom view thereof.

The broken lines represent unclaimed subject matter and form no part of the claimed design.

1 Claim, 4 Drawing Sheets
